UNITED STATES PATENT OFFICE.

WILLIAM ALBERT RAYMENT, OF TAUNTON, MASSACHUSETTS, ASSIGNOR TO
THE REED & BARTON CORPORATION, OF SAME PLACE.

DESIGN FOR A SPOON.

SPECIFICATION forming part of Design No. 31,460, dated August 29, 1899.

Application filed August 4, 1899. Serial No. 726,197. Term of patent 14 years.

To all whom it may concern:

Be it known that I, WILLIAM ALBERT RAYMENT, a subject of the Queen of Great Britain, residing at Taunton, in the county of Bristol, 5 and State of Massachusetts, have invented and produced a new and original Design for a Spoon, of which the following is a specification, reference being had to the accompanying drawings, forming part thereof, and in 10 which—

Figure 1 is a side view, and Fig. 2 a bottom plan view, of a spoon, showing my new design.

The leading or material feature of my design consists in the design forming the subject-matter of the accompanying illustration. 15

As shown, the handle A is bent or bowed

back and under and has its extremity lapped at A' against the inner side of the handle, near the juncture of the latter with the bowl B.

Having thus described my invention, what 20 I claim as new, and desire to secure by Letters Patent, is—

The design for a spoon as herein shown and described.

In testimony whereof I have signed my 25 name to this specification in the presence of two subscribing witnesses.

WILLIAM ALBERT RAYMENT.
